(57) **CLAIM**

The ornamental design for an anti-drip pourer, as shown and described.

DESCRIPTION

FIG. 1 is a perspective view of an anti-drip pourer of my new design;

FIG. 2 is a front view of the anti-drip pourer of FIG. 1, the rear view being a mirror image thereof;

FIG. 3 is a right side view of the anti-drip pourer of FIG. 1, the left side view being a mirror image thereof;

FIG. 4 is a top view of the anti-drip pourer of FIG. 1;

FIG. 5 is a bottom view of the anti-drip pourer of FIG. 1;

FIG. 6 is a perspective view of the anti-drip pourer of FIG. 1 in a first alternative position;

FIG. 7 is a perspective view of the anti-drip pourer of FIG. 1 in a second alternative position;

FIG. 8 is a perspective view of the anti-drip pourer of FIG. 6 located at a first position within an opening of a bottle; and,

FIG. 9 is a perspective view of the anti-drip pourer of FIG. 7 located at a second position within an opening of a bottle.

The bottle in FIGS. 8 and 9 is represented in broken lines for illustrative purposes only and forms no part of the claimed design.
